[57] **ABSTRACT**

A merchandise display apparatus. Two or more modular sections adapted to be cooperatively engaged to each other in an enclosing manner and mounted in a vertical fashion are provided with coupling sections and flanges at the end thereof for facilitating joining the members. The modular sections are adapted to receive a supporting structure which is secured thereto within the enclosure formed by the modular sections. Merchandise display members are vertically secured to the exterior of the modular sections, the display members being secured thereto by spring loaded, pivotal locking supports.

MERCANDISE DISPLAY APPARATUS

BACKGROUND OF THE INVENTION

1. Field of the Invention

The present invention merchandise display apparatus is generally related to display structures and, more specifically, to those structures fabricated from modular components.

2. Prior Art

With the increasing importance of commercial merchandising, it is becoming evident that more sophisticated structures are needed to permit the merchandiser to more efficiently display his wares. In addition, the ability to easily transport and assemble a display apparatus takes on additional importance when viewed in light of the economics involved.

The devices disclosed by the prior art are typically cumbersome structures which require prefabrication of the total structure or which require complex assembly procedures at the site where it is to be utilized. The present invention merchandise display apparatus substantially resolves a great many problems left unresolved by those devices disclosed in the prior art. The structure is comprised of a number of identical modular sections which can easily be assembled into the foundation for the display apparatus. The modular sections have end portions which are adapted to be coupled to adjacent sections through the use of an enveloping coupling sleeve which is cooperatively received by the end sections of a pair of adjacent modular sections. The exterior surface of each modular section is fitted with a number of merchandise display members which are secured to the modular section through the use of a spring-loaded, pivotal locking support which permits the member to be locked in a position substantially perpendicular to the surface of the modular section and be rotated substantially 90° in either direction from the locked position. The ability to rotate the merchandise holding members permit preassembly of this portion of the rack structure thereby facilitating transportation and assembly of the device at the point of use.

SUMMARY OF THE INVENTION

The present invention merchandise display apparatus is one which facilitates transport of the apparatus as well as assembly at the intended destination. Since one of the problems associated with the devices disclosed by the prior art is the cumbersome nature of the devices as well as the inefficiency in using same, the present invention is directed toward solving the difficulties experienced by manufacturers and users of such devices. The superstructure of the present invention apparatus is formed of modular sections which are substantially identical and, when the modular sections are coupled together, an enclosed area is circumscribed in a cylindrical-like manner. The lateral end portions of each modular section are adapted to be secured to a lateral end portion of an adjacent modular section, the coupling being made by a coupling member which is cooperatively received by the lateral end portions of adjacent modular sections. The open volume circumscribed by the coupled modular sections receives the supporting frame for the structure.

In order to provide for efficient use of the exterior surface of the modular sections, each section is provided with a number of merchandise display members.

Each member is secured along the longitudinal dimension of each modular section, the coupling between the merchandise holding member and the modular section being such as to permit prefabrication of the assembly.

5 The coupling between the merchandise display member and the modular section is a spring-loaded, pivotal locking support permitting pivotal movement of the merchandise display member while also providing for a locked position at a point substantially perpendicular from the surface of the modular section. When the present invention merchandise display apparatus is to be used, the modular sections are coupled at the lateral ends thereof forming the cylindrical-like structure, after which the merchandise holding members are rotated into a locked position substantially perpendicular from the surface of the modular section. By providing pivotable merchandise display members, they can be attached to the modular sections in a prefabricated manner prior to shipping the present invention apparatus. The coupling between the merchandise display members and the modular sections permit a more efficient package for shipment. In addition, the total structure is one which is easily assembled and provides a more efficient means for utilizing the apparatus after assembly.

10 It is therefore an object of the present invention to provide an improved merchandise display apparatus.

15 It is another object of the present invention to provide a merchandise display apparatus having pivotable merchandise display members.

20 It is yet another object of the present invention to provide a merchandise apparatus fabricated to modular sections.

25 It is still yet another object of the present invention to provide a merchandise display apparatus which is inexpensive and simple to fabricate.

30 The novel features which are believed to be characteristic of the invention, both as to its organization and method of operation, together with further objectives and advantages thereof will be better understood from the following description considered in connection with the accompanying drawing in which a presently preferred embodiment of the invention is illustrated by way of example. It is to be expressly understood, however, that the drawing is for the purpose of illustration and description only, and is not intended as a definition of the limits of the invention.

BRIEF DESCRIPTION OF THE DRAWING

35 FIG. 1 is an assembled merchandise display apparatus in accordance with the present invention.

40 FIG. 2 is a side, elevation view of a modular section of a merchandise display apparatus in accordance with the present invention.

45 FIG. 3 is a cross-sectional view of a modular section of a merchandise display apparatus taken through line 3—3 of FIG. 2.

50 FIG. 4 is a cross-sectional view of the coupling between two adjacent modular sections in accordance with the present invention.

55 FIG. 5 is a perspective view of the pivotal support shown in FIG. 2.

60 FIG. 6 is a side, elevation view of the pivotal support showing the display member in the pivoted position.

DESCRIPTION OF THE PRESENTLY PREFERRED
EMBODIMENT

A better understanding of the present invention merchandise display apparatus can be best gained by reference to FIG. 1 wherein a perspective view of an embodiment thereof is shown therein generally designated by the reference numeral 10. The present invention merchandise display apparatus 10 comprises three identical modular sections 11 coupled at ends thereof to form the enclosed volume 12 in a cylindrical-like manner. Although FIG. 1 illustrates the use of three modular sections 11, it is understood that the number of modular sections 11 could be any practical number which will permit formation of the closed structure illustrated. Modular sections 11 are coupled at the lateral ends thereof to an adjacent modular section 11 by way of coupling sleeves 13 which are cooperatively received by the lateral end portions of adjacent modular sections 11. Display members 14 are pivotally connected to the exterior surface of modular sections 11, display members 14 being comprised of a substantially cylindrical rod extending longitudinally along modular sections 11 and merchandise supports 16 depending therefrom. The pivotal connections between display members 14 and the exterior surface of modular sections 11 comprise a number of guides 17 (FIG. 2) having apertures therein to receive cylindrical rod 15 and pivotal locking support 18 to permit display members 14 to be locked in a predetermined position as well as to pivot to a position substantially parallel to the surface of modular sections 11. Interior supporting structure 19 is secured to the interior surfaces of modular sections 11 to place the present invention merchandise display apparatus 10 in an appropriate vertical position for presenting attached merchandise.

Modular sections 11 are preferably fabricated of light-weight deformable metal such as aluminum, but modular sections 11 could also be fabricated from other conventional material such as a sturdy plastic. The remaining elements of the present invention merchandise display apparatus are preferably fabricated of a sturdy structural metal.

Referring now to FIG. 2 and FIG. 3, the structure of modular sections 11 can be best seen. Modular sections 11 as shown in FIG. 2 and FIG. 3 each comprise a pair of walls 25 integral with each other, the interior surfaces of walls 25 being angularly displaced from each other by 120° of arc. Where a pair of walls 25 are angularly separated by 120°, three modular sections 11 can be joined in a closed structure producing a six-sided polygon. Although the preferable structure for modular section 11 utilizes a pair of walls 25 separated by 120° or arc, it is understood that other geometrical configurations are within the the scope of the present invention merchandise display apparatus. Flanges 26 depend from the opposed lateral edges of walls 25, flanges 26 being terminated by inwardly directed coupling sections 27. Coupling sections 27 are utilized for joining modular sections 11 together as shown in FIG. 1 through the use of coupling sleeves 13. This will be more fully described with respect to FIG. 4. Flanges 26 are disposed at an obtuse angle with respect to the exterior surface of walls 25, the obtuse angle being approximately 120° of arc.

Each wall 25 is adapted to cooperatively receive a number of pivotal locking supports 18 and guides 17. As shown in FIG. 2, each side wall 25 has secured thereto a pair of pivotal locking supports 18 at the bottom end thereof and two guides 17 being secured to walls 25 in longitudinal linear alignment with each pivotal locking support 18. Although FIG. 2 illustrates each wall 25 receiving an aligned set of guides 17 and pivotal locking supports 18, it is understood that a greater or lesser number of aligned components are within the scope of the present invention. Display members 14 are mounted within each aligned combination of pivotal locking support 18 and guides 17, each display member comprising cylindrical rod 15 and depending merchandise supports 16. When modular section 11 is disposed in a vertical position as shown in FIG. 1, pivotal locking supports 18 restrain vertical movement of rods 15 while permitting merchandise support 16 to be rotated about the axis of cylindrical rods 15. Merchandise supports 16 are typically spaced in a uniform manner along cylindrical rod 15, but non-uniform configurations are within the scope of the present invention.

The manner in which modular sections 11 are coupled to fabricate the present invention merchandise display apparatus 10 as shown in FIG. 1 can be best seen by reference to FIG. 4 wherein a cross-sectional view of a pair of joined modular sections 11 are shown. As shown in FIG. 2 and FIG. 3, each modular section 11 has a pair of walls 25, each wall 25 with a flange 26 depending therefrom at an obtuse angle of approximately 120°. When the surfaces of a pair of flanges 26 of adjacent modular sections 11 are placed in abutment, coupling sections 27 of each respective modular section are aligned in a common plane. In addition, the laterally opposed surfaces of each wall 25 of respective modular sections 11 are aligned to produce an obtuse angle therebetween of approximately 120° of arc. After flanges 26 and coupling sections 27 have been aligned, coupling sleeve 13 is inserted over coupling sections 27 securing the respective modular sections 11 into a sturdy structure. Coupling sleeve 13 is typically a unitary section of deformable metal which is substantially C-shaped, the interior portion of which is adapted to frictionally engage the surfaces of coupling sections 11 in a manner which will prevent inadvertent dislodgement of coupling sleeve 13.

The structure of pivotal locking support 18 can be best seen in FIG. 5 and FIG. 6. FIG. 5 illustrates pivotal locking support in the locked position, FIG. 6 showing same in the unlocked position. Pivotal locking support 18 includes rod guide 30. Rod guide 30 comprises a center member 31 having flanges 32 depending from the lateral edges thereof in a co-planar manner forming a substantially U-shaped bracket. Each flange 32 has disposed therein an aperture adapted to receive cylindrical rod 15, the apertures adapted to receive cylindrical rod 15, the apertures in flanges 32 having an axial alignment parallel to center member 31. Diametrically opposed detents 33 are cut or otherwise disposed in an aperture of one of the flanges 32. Detents 33 receive pins 34 depending from cylindrical rod 15 to lock the position of cylindrical rod 15 when pins 34 and detents 33 are in a mating position. As can be seen in FIG. 5, pins 34 are received by detents 33 locking the position

of cylindrical rod 15 in a manner that would prevent any angular movement of cylindrical rod 15. Helical spring 35 is disposed about cylindrical rod 15, one end of helical spring 35 being abutted against pins 34, the other end of helical spring 35 being in abutment with surface 36 of flange 32. In the position shown in FIG. 5, helical spring 35 is in its extended position forcing cylindrical rod 15 in a downward direction, the downward movement of cylindrical rod 15 being terminated by stopping member 37. As shown in FIG. 6, cylindrical rod 15 is moved in a vertically upward position, pin 34 being angularly rotated to prevent engagement between pins 34 and detent 33. In this position, helical spring 35 is in a compressed position preventing inadvertent rotation of cylindrical rod 15. Stopping member 38 is secured to the bottom portion of cylindrical rod 15 to limit the upward movement thereof.

The present invention merchandise display apparatus provides an efficient device for displaying merchandise as well as providing an apparatus which is inexpensive and simple to fabricate. One of the primary objectives of the present invention is to provide a device which can be transported and assembled in a simplified manner. The characteristics of the present invention which fulfill these objectives relate to the coupling of modular sections 11 and the ability to mount display members 14 prior to shipment. With respect to assembly, modular sections 11 can be easily shipped because of the common structural profile of modular sections 11 and, in addition, the simplified manner in which modular sections 11 can be coupled through the use of coupling sleeves 13 substantially improves the ability to quickly assemble and utilize the present invention apparatus. By providing the ability to mount display members 14 prior to shipment of the apparatus unnecessary assembly procedures are avoided. By placing display members 14 in the position shown in FIG. 6, merchandise support 16 can be folded back upon walls 25 of modular sections 11 thereby substantially eliminating the transportation and assembly problems. After modular sections 11 have been coupled as shown in FIG. 1, display members 14 can be rotated to the locked position shown in FIG. 5 and thereby quickly be available for use by the intended user.

I claim:

1. An apparatus for displaying merchandise comprising:

- modular sections each having walls with an inner and outer surface and flanges depending outwardly from the opposed lateral ends thereof, each flange adapted to cooperatively receive a flange of an adjacent modular section whereby said modular sections are joined into an enclosing surface;
- coupling sections depending from each of said flanges in an opposed planar relationship;
- a coupling sleeve disposed about said coupling sections of adjacent modular sections and being in frictional engagement therewith whereby said modular sections are coupled to each other forming an enclosed surface; and
- display members pivotally secured to the outer surface of said modular section walls.

2. An apparatus as defined in claim 1 wherein three modular sections are secured together, each modular

section having a pair of integral walls, the inner surface of said walls being disposed at an angle of 120° of arc from each other.

3. An apparatus as defined in claim 1 wherein said display members comprise a cylindrical rod having diametrically opposed pins disposed at an end thereof and merchandise supports perpendicularly depending therefrom at uniformly spaced intervals along said cylindrical rod.

4. An apparatus as defined in claim 3 wherein said display members are pivotally secured to said modular sections by pivotal locking supports, said pivotal locking supports comprising a U-shaped bracket, the legs of said bracket having apertures having diameters adapted to receive said cylindrical rod, one aperture having detents adapted to receive said pins of said cylindrical rod, a helical spring disposed about said cylindrical rod, a first end thereof abutted said pins, the second end thereof abutted against one of the legs of said U-shaped bracket.

5. An apparatus for displaying merchandise comprising:

- three modular sections each having a pair of integrally connected walls having an inner and outer surface, the inner surfaces being angularly separated by 120° of arc, said modular sections having flanges depending from laterally opposed ends of said walls, said flanges being angularly separated from the outer surface of said walls by 120° of arc, said flanges being adapted to cooperatively receive a flange from an adjacent modular section;
- coupling means for securing said three modular sections into an enclosing surface, said coupling means coupled to said flanges;
- display members including a cylindrical rod having spaced merchandise supports perpendicularly depending therefrom, said cylindrical rod having diametrically opposed pins extending therefrom at the bottom portion of said cylindrical rod; and
- pivotal locking supports secured to the outer surface of said walls at an end thereof and receiving said cylindrical rods, said pivotal locking support comprising a center member and a pair of co-planar members depending from the ends of said center member, said co-planar members having aligned apertures having diameters greater than said cylindrical rods, one aperture having detents adapted to receive said pins of said cylindrical rods, a helical spring disposed about said cylindrical rod, a first end thereof abutted against said pins, the second end thereof abutted against one of said co-planar members.

6. An apparatus as defined in claim 5 wherein said coupling means comprises coupling sections depending outwardly from said flanges in an opposed planar relationship and a coupling sleeve frictionally engaging said coupling sections whereby adjacent modular sections are secured to one another.

7. An apparatus as defined in claim 5 wherein said merchandise supports are uniformly spaced along said cylindrical rods.

8. An apparatus as defined in claim 5 wherein said display members are uniformly mounted upon the walls of said modular sections.
